UNITED STATES PATENT OFFICE.

WILLIAM J. PARSONS, OF MONTAGUE, MASSACHUSETTS, ASSIGNOR TO LANGDON MITRE BOX COMPANY, OF ERVING, MASSACHUSETTS, A CORPORATION.

MITER-MACHINE.

SPECIFICATION forming part of Letters Patent No. 694,323, dated February 25, 1902.

Application filed August 21, 1901. Serial No. 72,763. (No model.)

To all whom it may concern:

Be it known that I, WILLIAM J. PARSONS, of Montague, in the county of Franklin and State of Massachusetts, have invented certain new and useful Improvements in Miter-Machines, of which the following is a specification.

My present invention relates to what are called "miter-boxes" or "miter-machines."

- 10 In the drawings, Figure 1 represents an elevation of the machine. Fig. 2 is a view of the outer guide-piece and its supporting-spring. Fig. 3 is a plan view of the machine in operation, the dotted lines showing the position 15 while in use reversed. Fig. 4 represents the molding after being cut or beveled at each end, the machine being operated from the same side of the molding. Fig. 5 is a view of the invention in its practical use.
- 20 One of the important points of the invention is the peculiar arrangement of parts by which the machine can be used to cut opposite miters or angles while being operated from the same side of the molding or other 25 wood or metal cut. The other points of novelty will be hereinafter explained.

Referring to the drawings, A is the base of the machine, having a central fin extending downward lengthwise of its center, as shown 30 in Fig. 1, a. The base A overlaps on each side of the fin a, as indicated in Fig. 3, and forms a right angle on its under sides with the side faces of the fin a. It will thus be seen that the machine can be used with equal 35 facility whichever face of the fin is held against the article to be mitered. It will also be seen that this arrangement of parts enables the operator to continually work from the same side and from the same end of the material being cut. This is a very important 40 and valuable feature in all cases, but more especially in cutting large or irregular-formed moldings. It enables more work to be done in the same time and tends to produce more 45 exact mitering. Near one end and on top of the said base A is placed the base-plate B, secured to the base by the rivet or screw b⁴. The base-plate B is made circular and readily 50 revolves on the base A. Around its edge are provided notches b³, so arranged as to conform to the angles or bevels desired to be cut.

On the top of the base is provided the box b, suitably and movably secured thereto. In said box is placed the spring catch or bolt b', the outer end b² preferably made pointed to 55 correspond with the size and shape of the notches b³ formed in the rim of the base-plate B. The base-plate and the parts attached thereto are firmly held in place and instantly set, as desired, by the contacting of 60 the pointed catch b' within one of the said notches b³. The catch b' is delicately adjusted laterally by the set-screws b⁵ b⁵, one on each side of the box b. It will be observed that if the catch b' is moved laterally the position 65 of the base-plate will be varied accordingly, as the notches b³ must coincide with the point of the spring-catch when in use and any turning of the base-plate of course varies the bevel or angle of cut. I consider this arrangement 70 of much value, as it enables the machine to be adjusted to the closest angle for cutting. By this adjustment the operator can match most perfectly any bevel required. Other well-known means of holding the base-plate 75 could be employed; but the arrangement shown is upon the whole, I think, preferable, especially when combined with the method of adjustment described.

Secured to or solid with the base-plate B is 80 the inner guide-plate B'. To the said guide-plate is secured the spring C, which is bent to form a loop upward, as shown in Fig. 1. To the outer end of the said spring C is secured the outer guide-plate B², as shown in 85 Fig. 2. If desired, for the purpose of stiffening the guide-plates the rib d may be added, though this is not essential.

The saw used in cutting the molding or other material is represented by D, D' being the 90 handle. The saw is held in position and at the angle desired by the guide-plates B' B², the spring holding and pressing the guide-plates against the sides of the saw.

The surface of each side of the central fin 95 a is formed, as shown in Fig. 1, with alternate depressed and raised surfaces, x x representing the depressions and y y the raised smooth surfaces. The bearing would therefore be wholly upon the raised surfaces or elevations y y. Preferably the same form of alternate depressions and raised surfaces may be 100

used on the inner faces of the guide-plates B' B², though this is not essential.

There is another valuable feature connected with the herein-described machine, which 5 consists in its ready removability from the work. In the old style of miter-box the molding to be cut was placed in the box, and thus held was retained until the cutting was done. In my present machine the machine is placed 10 on the molding, and where a panel-saw is used it might be impossible to cut clear through a wide molding unless the machine could be removed from the work at any time. This can be readily done at any stage of the 15 cut after starting the saw at the proper angle. The depth of cut with a panel-saw or one having a rib on its back is always limited unless the guide-plates or other obstructions are removable. Fine work requires a stiff 20 saw.

I do not wish to confine myself to the exact details herein shown and described, as these may be varied without departing from the spirit of my invention.

25 What I claim as my invention, and desire to secure by Letters Patent of the United States, is—

1. The herein-described miter-machine, consisting of the base A, provided with the solid 30 central fin a, having a face on each side formed at right angle to the under side of the said base; the base-plate B, provided with the notches b³, and adapted to revolve on the pivot which secures it to the base; the saw- 35 guide plates B' B²; the spring C, secured to said guide-plates; the adjustable catch or bolt b', having the pointed end b², and adapted to coincide with the said notches, all combined substantially as and for the purposes 40 set forth.

2. In a miter-machine, the combination of a base provided with a longitudinal central

fin and having two right-angular faces in connection with the under side of said base; with suitable means for holding and adjusting a 45 saw, substantially as and for the purposes set forth.

3. In a miter-machine, the base A, having a double-faced solid fin; a movable base-plate secured to the said base and provided 50 with suitable notches and suitable guide-plates supported thereon, and an adjustable catch suitably held and having a pointed end corresponding with said notches and adapted to engage them, all combined substantially as 55 and for the purposes set forth.

4. In a miter-machine, the box b, provided with the adjusting-screws b⁵ b⁵, the catch b', adapted to be moved longitudinally and laterally, the revolving base-plate B, arranged to 60 present a suitable rack for the engagement of said catch, and having suitable saw-guides, and the base A, combined substantially as and for the purposes set forth.

5. In a miter-machine, the base A, having 65 the central fin a, solid with said base and forming a right angle with the under side of said base upon each face of said fin, and adapted to operate as and for the purpose de- 70 scribed.

6. In a miter-machine, the base-plate B, adapted to revolve and provided with suitable notches b³; in combination with the catch b', adapted to be adjusted laterally by suitable means, substantially as and for the pur- 75 poses set forth.

In testimony whereof I have affixed my signature, in presence of two witnesses, this 10th day of August, A. D. 1901.

WILLIAM J. PARSONS.
